CARL J. GREENSPAN, OF PHILADELPHIA, PENNSYLVANIA.

BRAID AND METHOD OF MAKING THE SAME.

Application filed February 13, 1926. Serial No. 88,006.

My invention is a braid particularly adapted for the manufacture of rugs and having each of its surfaces formed essentially by filler or "warp" strands which are wholly invisible from the opposite surface; the filler strands of the two surfaces being preferably spaced by substantially unbent stuffer yarns or threads, and the whole bound together by interlaced binder threads passing from one surface to the other of the braid and forming patterns therein. Such a construction is not only economical of the expensive surface strands, but permits the formation of a rug having opposite surfaces each of which has a complete and finished appearance, and each of which surfaces may be made distinctly different from the other in color and/or in texture.

In the preferred practice of my invention, a braid is formed from a pair of sets of longitudinal surface strands, one set of strands forming what may be arbitrarily called the "top" and the other set of strands forming what may be arbitrarily called the "bottom". These terms are, however, merely relative and either surface may be regarded as the top and the other surface as the bottom. The "top" and "bottom" sets of strands are preferably spaced by a pair of sets of longitudinal stuffer threads similar in color to or harmonizing with the surface strands to which they are respectively adjacent, and the longitudinal strands and threads are bound together by several pairs of sets of binder threads. The sets of each pair of binder threads are preferably the same in color and texture and travel in opposite directions, and the threads of one pair preferably contrast in color with the threads of the other pair. The pairs of binder threads alternate with one another along each surface of the braid and preferably the sets of each pair pass under the edge strands of one set or "top" surface strands at different places along the braid, then over the inner strands of such set of surface strands, across and intertwine with one another on the top to form an arrowhead shaped figure or pattern, then pass under the inner strands of the top surface set of strands, over the outer strands of the same surface set and across the side surfaces or edges of the braid, where the threads of the sets of contrasting pairs intertwine, thence over the edge strands of the opposite or "bottom" surface, under the inner strands of bottom surface, cross one another and interlace to form an arrowhead

shaped figure on the bottom face, thence pass over the inner strands of the bottom surface, under the edge strands of the bottom surface, and around the thickness of the braid, interlacing across the edges with the contrasting threads coming from the opposite surface. The operation is then repeated. The braid so formed is sewed together with the side edge of one convolution juxtaposed to the side edge of the next convolution, so that the rug has two surfaces differing distinctly from one another, but each surface having therein patterns formed by the interlacing of the sets of binder threads.

In the accompanying drawing, Fig. 1 is a plan view of a rug embodying my improvements with one end thereof folded over to show the opposite surface; Fig. 2 represents diagrammatically a cross sectional view of the braid from which the rug is formed taken on the section line 2-2 of Fig. 6; Fig. 3 illustrates diagrammatically a cross sectional view of the braid taken on the section line 3-3 of Fig. 6; Fig. 4 is a diagrammatic perspective view of a braid section with portions removed for clearer illustration; Fig. 5 is a diagrammatic view of the braid surfaces projected as a plane and Fig. 6 is a diagrammatic perspective view of a braid strip twisted to show the two wearing surfaces thereof.

As illustrated in the drawings, the rug is formed by securing together, as by sewing, convolution of a braid with the side edges thereof juxtaposed. One wearing surface of the braid comprises a plurality of strands, preferably chenille, 1^a, 1^b, 1^c, 1^d, and the other wearing surface of the braid comprises a plurality of strands 2^a, 2^b, 2^c and 2^d, preferably of chenille contrasting in color, or if desired in texture, with the strands 1^a, 1^b, 1^c and 1^d. The surface chenille strands are spaced by sets of stuffer threads 3 and 4 suitably of cheap yarn, the stuffer threads 3 harmonizing or conforming in color with the chenille threads 1^a, 1^b, 1^c, 1^d, and the stuffer threads 4 harmonizing or conforming in color with the chenille threads 2^a, 2^b, 2^c and 2^d, the stuffer threads are primarily designed to form a core giving body to the braid and are not intended to be visible from the surface.

The surface strands and stuffer threads are held against twisting or displacement by suitable means and while so held are bound together in a braid by two pairs of sets of binder threads; one pair consisting of the

sets 5 and 6 and the other pair consisting of the sets 7 and 8.

The sets 5 and 6 respectively pass under the edge strands 1^a and 1^d, and over the inner strands 1^b and 1^c. The sets 5 and 6 then cross and intertwine or interlace with one another to form a figure or pattern 9. The set 5 then passes under the strand 1^c and over the strand 1^d and the set 6 passes under the strand 1^b and over the strand 1^a. This tends to draw the strands 1^b and 1^c together as indicated at 10 in Fig. 6.

The binder threads 5 and 6 then respectively pass downwardly over the opposite lateral edges of the braid and in about the plane of the invisible stuffer threads 3 and 4 cross and intertwine with the respective binder threads 7 and 8 coming up from the bottom wearing surface formed by the chenille threads 2^a, 2^b, 2^c, 2^d.

After crossing the threads 8, the threads 5 pass over the edge strand 2^d, and under the inner strand 2^c, while the threads 6, after crossing the threads 7 pass over the edge strand 2^a and under the inner strand 2^b. The sets of threads 5 and 6 then cross and intertwine to form an arrowhead shaped figure or pattern 11 on the bottom of the braid similar to the figure 9 on top of the braid but having its point extending in the opposite direction. The threads 5 then pass over the inner strand 2^b, under the edge strand 2^a, around the edge of the braid, crossing the threads 8 and repeating. The threads 6, after forming the pattern 11, pass over the inner strand 1^c under the edge strand 1^d, around the edge of the braid, crossing the threads 7 and repeating.

The sets of threads 7 and 8 follow courses similar to the courses of the threads 5 and 6 and alternate therewith. The points where the threads 7 and 8 cross one another on one side of the braid are slightly staggered relatively to the points where the threads 5 and 6 cross one another on the opposite side of the braid.

The respective binder threads 7 and 8 pass under the respective edge strands 1^a and 1^d, over the inner strands 1^b and 1^c, cross and intertwine with one another to form the pattern 12, pass under the inner strands 1^c and 1^b, over the edge strands 1^d and 1^a, around the sides of the braid crossing and intertwining with the sets of threads 5 and 6, then passing respectively over the edge strands 2^d and 2^a, under the inner strands 2^c and 2^b, crossing and intertwining to form the pattern 13, over the inner strands 2^b and 2^c, under the outer strands 2^a and 2^d, around the sides of the braid, crossing and intertwining with the sets of threads 6 and 5 and repeating.

The braid so formed is of substantially rectangular cross section. The longitudinal surface threads 1^a, 1^b, 1^c, 1^d, 2^a, 2^b, 2^c and 2^d are but slightly bent and no portion thereof is wasted

by passing through the thickness of the braid from one side to the other thereof. The predominant appearance and character of the top and bottom surfaces of the braid are given thereto by the longitudinal surface strands, 70 and hence the two surfaces of the rug may be made wholly different in appearance and texture. Any desired number of "ends" may be used in the surface strands, binder threads and stuffers. The stuffer threads backing 75 the surface strands prevent any chance of the opposite surface strands showing through. The braid may have its lateral edges sewed or otherwise fastened together to form a rug of any desired shape or size, 80 but preferably the braid convolutions are wound together as shown in Fig. 1 to produce a rug having a curved periphery. If desired braid sections of different colors may be united in one rug to form a pattern on each 85 surface, such as the ring 14 or margin 15.

Having described my invention, I claim:

1. A rug braid comprising strands on opposite surfaces thereof extending longitudinally of said braid and substantially parallel with one another; and binder threads engaging said strands together and concealing such strands only at spaced points.

2. A braid comprising strands extending longitudinally of the braid and forming exposed opposite surfaces thereof, the strands forming one surface being invisible from the other surface, and binder threads engaging said strands together and covering the surfaces thereof only at spaced points.

3. A braid comprising top and bottom sets of strands extending longitudinally of the braid without interlacing with one another; spaced by stuffer threads between them, and binder threads engaging said strands and 105 stuffer threads together.

4. A rug braid comprising surface strands forming each face thereof and which are confined to one side of the center line of the braid, stuffer threads between the strands forming one face and the strands forming the other face, and binder threads securing said strands together without passing through said stuffer threads.

5. A rug braid comprising a pair of sets of longitudinal surface strands, and a plurality of pairs of sets of binder threads engaging said strands together, the sets of each pair of binder threads passing under edge strands of one set of surface strands, over inner strands 115 of said last named set of surface strands, over one another, under inner strands of the last named set of surface strands, and over edge strands of the last named surface strands.

6. A rug braid comprising a pair of sets of longitudinal surface strands, and a plurality of pairs of sets of binder threads securing said strands together, the sets of each pair of binder threads passing over edge strands of one set of surface strands, under inner strands 130

of said last named set of surface strands, across one another, over the inner strands of the last named set of surface strands, and under edge strands of said last named set of 5 surface strands.

7. The method of forming a rug braid which comprises braiding binder threads around sets of longitudinal surface threads without intertwining the sets of surface 10 threads together.

8. The method of forming a rug braid which comprises binding together sets of parallel surface strands extending longitudinally of the braid by braiding them with a plurality of sets of binder threads. 15

9. A rug braid of substantially rectangular cross section with surfaces and edges comprising a plurality of sets of surface threads spaced by stuffer threads forming a core, and a plurality of pairs of sets of binder threads interbraiding and securing said surface threads together, the sets of each pair of binder threads crossing one another on each surface of the braid and a set of one pair of binder threads crossing a set of the other pair of 20 binder threads on each edge of the braid.

In witness whereof I have hereunto set my name this 30th day of January, 1926.

CARL J. GREENSPAN.
